UNITED STATES PATENT OFFICE

LOUIS F. GERDETZ, OF PITTSBURGH, PENNSYLVANIA

MINING PROP

Application filed September 14, 1927. Serial No. 219,491.

This invention relates to an improvement in mining props.

The invention relates to an adjustable safety steel prop, which is designed to replace the use of wooden supports (props) etc. in coal and metal mines, tunnel constructions and other underground operations. The objects of the invention are first, to provide a steel prop which absorbs weight gradually and gives under pressure of roof or overburden; second, to offer resistance to pressure and weight by friction and compression of certain of its members; and third, to, when necessary, be made to collapse from under the weight and be removed from a safe distance in order to be used over and over again.

The invention resides in the structure of the prop, in which a lower H-shaped supporting member is adapted to rest in the lower portion of the mine or other underground passage and have an upper wedge-shaped member slidably connected therewith. A slot is formed in the H-beam to receive a bolt which is connected with the wedge-shaped upper member, to regulate the sliding movement thereof. Suitable locking mechanism is pivotally associated with the members in order to regulate the positions of the two or to release the wedge-shaped upper supporting member to allow it to fall whenever desired.

The advantage of making this locking mechanism pivoted is that it may be operated from a suitable and safe distance, thus eliminating any danger to the lives of the miners when releasing the prop.

In the accompanying drawings:

Fig. 1 is the front view of the prop when extended;

Fig. 2 is a vertical section of the prop on the line A—B in Fig. 1;

Fig. 3 is a horizontal section of the prop on the line C—D in Fig. 1;

Fig. 4 is a side view of the prop when collapsed; and

Fig. 5 shows a slight modification.

The construction of the prop includes a lower member, being an H-shaped steel column 1. This column is provided with a slot

2 cut into its web to allow a bolt 3 of the upper member to slide up and down therein. A foot shoe 4 is riveted to the flanges of the column 1. Four steel plates 5 riveted to the flanges provide a recess for side plates 6 of the locking mechanism to be held in place and slide laterally therebetween.

The upper member consists of two channel-shaped steel columns 7 riveted together web to web with a spacer 8 therebetween, to allow them to slide up or down on each side of the web of the H-shaped member 1. The two channel-shaped steel columns 7 are held together at their lower ends by the bolt 3, which in turn is provided with a sleeve 9 in order to hold the channel shaped steel column 7 in position and a suitable distance apart. The bolt 3 and sleeve 9 travel through the slot 2 when the upper member is either raised or lowered.

Mounted between the flanges of the two steel channels 7 are two hardwood fillers 10 covered by steel liners 11 and forming an inclined wedge. The hardwood fillers 10 and steel liners 11 are held in place by a rivet 12 and the bolt 3 extending therethrough. A steel cap 13 is riveted to the steel channels 7 on top of the column.

The locking mechanism consists of two steel side plates 6 held together on both ends by two bolts or pins 14. The side plates 6 rest on and can move laterally relative to the flanges of the H-beam in the recesses formed between the four plates 5. Trip block 15 is located on the front side of the prop and is held in place between the side plates 6 by one of the steel pins 14, on which it can revolve. When in locked position, the trip block 15 bears against one side of the wedge-shaped surface of the upper member. The handle of the trip block is provided with a hole 16 through which a rope or chain (not shown) may be fastened when it is desired to trip the block from a safe distance and cause the prop to collapse and be removed from under dangerous roof or fall.

A toggle 17 is located on the back side of the prop and is held in place between the side plates 6 by one of the steel pins 14, on which it can revolve. It can fit itself snug

against various shapes of wedges inserted in between itself and the wedge shaped part of the upper member. When in locked position, the toggle 17 bears against the wooden wedge 18 and through it against the side of the wedge shaped part of the upper member.

When the adjustable safety prop is set in position and locked, the tendencies of the wedge-shaped member is to settle or give under weight or pressure. It then simulates on a larger scale the give of a wooden prop under similar conditions, without however being exposed to the disastrous results which invariably occur to the latter, when bearing under excessive pressure, it fails for want of sufficient resiliency and, as such, constitutes a menace to the lives of men engaged in mining. At best, in such cases a wooden prop is a total loss in addition to costly and dangerous falls and caves caused by its failure.

The settlement or give of the adjustable safety steel prop is accomplished at the expense of the wooden wedge 18 which is being gradually compressed as the wedge shaped upper member descends. An ever increasing resistance to the settlement or give of the prop is offered in addition to the compression of the wedge 18, by the friction of webs of the upper and lower members against each other.

The alignment of the upper and lower members of the props in respect to each other allows an even distribution of stresses and prevents any distortion of the prop when under pressure or weight.

The adjustable safety prop is designed to be manufactured in various lengths, each adjustable to a certain extent to heights of coal seams, etc.

It might be mentioned that the fillers 10 are preferred for lightness, but it is perfectly obvious that solid metal strips might be employed in lieu of the wooden fillers, in which event the liners 11 would be entirely omitted.

It is also obvious that the channel-irons as shown at 7 might be turned in the opposite direction as illustrated at 7^a in Fig. 5, in which event no filler-strips such as 10 would be used.

I claim:

1. A mining prop comprising an H-shaped lower member having a slotted web, an approximately wedge-shaped upper member having portions thereof embracing the web of the H-shaped lower member, and connected together through the slot, a yieldable block in position to bear against one side of the wedge-shaped upper member, and a pivotally mounted locking member arranged on and adapted to bear against the opposite side of the upper member.

2. A mining prop comprising an H-shaped lower member having a slotted web, an approximately wedge-shaped upper member having portions thereof embracing the web

of the H-shaped lower member, and connected together through the slot, a relatively flat faced member carried by the lower member, a compressible block interposed between the flat faced member and the wedge-shaped member, normally tending to hold the members in set positions and to allow relative longitudinal movement thereof under substantial pressure, and a pivotally mounted locking member arranged on and adapted to bear against the opposite side of the wedge-shaped member from the compressible block for releasing the members.

3. A mining prop comprising members connected together for relative longitudinal movement, one of said members having a slotted web, the other member being approximately wedge-shaped and having portions thereof embracing the web of the first-mentioned member, and connected together through the slot, and a block in position to bear against one side of the wedge-shaped member.

4. A mining prop comprising members connected together for relative longitudinal movement, one of said members having a slotted web, the other member being approximately wedge-shaped and having portions thereof embracing the web of the first-mentioned member and connected together through the slot, a yieldable block in position to bear against one side of the wedge-shaped member, and locking means arranged on and adapted to bear against the opposite side of the wedge-shaped member.

5. A mining prop having upper and lower members slidably connected together, said upper member being approximately wedge-shaped, a compressible block acting on the wedge-shaped member to be compressed upon a subsidence of the upper member, and a pivotally mounted releasable member to release the pressure on the prop.

6. A mining prop having upper and lower members slidably connected together, said upper member being approximately wedge-shaped, side plates slidably transversely of and connected with the lower member, a compressible block mounted between said plates and held thereby to act on one side of the wedge-shaped member, to be compressed upon a subsidence thereof, and an upwardly turned locking member pivotally connected with the plates in position to act on the opposite side of the wedge-shaped member and to release the pressure on the prop.

In testimony whereof I affix my signature.

LOUIS F. GERDETZ.
